COMBINED PORTABLE BAR AND REMOVABLE
STAND THEREFOR

Jerry H. Galuten, Elmhurst, N.Y., assignor to Placix
Corporation, Woodside, N.Y.

Filed Jan. 9, 1973, Ser. No. 322,139

Term of patent 14 years

Int. Cl. D6—04

U.S. Cl. D6—144

FIG. 1

FIG. 2

FIG. 4

FIG. 1 is a front perspective view of a combined portable bar and removable stand therefor showing my design, the bar being shown with the trays and ice bucket cover in place and with the stand removed;

FIG. 2 is a front perspective view thereof, the bar being shown with the ice bucket cover and trays removed and the stand removed;

FIG. 3 is a right end elevation view thereof with the stand removed; and

FIG. 4 is a bottom perspective view thereof with the bar shown removably mounted on the removable stand.

I claim:

The ornamental design for a combined portable bar and removable stand therefor, substantially as shown.
